UNITED STATES PATENT OFFICE.

PERRY WEARNE, OF RIXHEIM, GERMANY.

DESIGN FOR A WALL-PAPER BORDER.

SPECIFICATION forming part of Design No. 35,400, dated December 3, 1901.

Application filed November 5, 1901. Serial No. 81,265. Term of patent 7 years.

To all whom it may concern:

Be it known that I, PERRY WEARNE, a subject of the King of Great Britain, residing at Rixheim, Alsace, Germany, have invented and produced a new and original Design for a Wall-Paper Border, of which the following is a specification, reference being had to the accompanying drawing, forming a part thereof, in which is represented a section of a wall-paper border, showing my design.

The design in its entirety consists in the representation of roses A, appearing band-like and interlaced with ribbons B, crossing each other.

The leading feature of the design consists in the representation of roses interlaced with ribbons.

Having described my invention, I claim as new and desire to secure by Letters Patent— The design for the wall-paper border herein shown and described.

In testimony whereof I have signed my name to this specification in the presence of two subscribing witnesses.

PERRY WEARNE.
